UNITED STATES PATENT OFFICE.

RUBEN F. BARKER, OF MARINETTE, WISCONSIN, ASSIGNOR OF ONE-HALF
TO MICHAEL CORRY, OF SAME PLACE.

STEAM SET-WORKS FOR SAWMILLS.

SPECIFICATION forming part of Letters Patent No. 643,453, dated February 13, 1900.

Application filed August 16, 1899. Serial No. 727,407. (No model.)

To all whom it may concern:

Be it known that I, RUBEN F. BARKER, a citizen of the United States, and a resident of Marinette, county of Marinette, and State of Wisconsin, have invented certain new and useful Improvements in Steam Set-Works for Sawmills, of which the following is a specification, and which are fully illustrated in the accompanying drawings, forming a part thereof.

This invention relates to means for providing an adjustable stop to limit the range of movement of the setting mechanism; and its object is to simplify the construction of such devices and to provide for greater ease and simplicity of adjustment.

The invention consists in the parts and arrangement of parts, as hereinafter fully described and as illustrated in the accompanying drawings, in which—

Figure 1 is a detail plan view of a carriage and the set-works mounted thereon. Fig. 2 is a vertical longitudinal section of the power mechanism for controlling the set-works, some of the parts being shown in elevation. Fig. 3 is a plan, partly in section, on the line 3 3 of Fig. 2. Fig. 4 is a detail plan, partly in section, on the line 4 4 of Fig. 2. Fig. 5 is a sectional view on the line 5 5 of Fig. 2. Fig. 6 is a detail view on the line 6 6 of Fig. 5, and Figs. 7 and 8 show details of a ratchet-pawl employed in the device.

For the purpose of clearness I have shown in the drawings many of the parts of a saw-mill-carriage and its appurtenances which are in common use. Such parts I have not deemed it necessary to show in detail, as their importance in this connection resides merely in the relation of the parts.

The sills of a log-carriage are shown at 10 and 11, and some of the wheels for supporting the carriage are shown at 12.

At 13 is shown the ways for one of the head-block knees 14, and at 15 is shown the set-shaft for controlling the head-blocks. This shaft is provided with any suitable means for retracting the blocks, such as the spring 16, and its advance movement is accomplished by means of a ratchet-wheel 17, fixed upon it, and pawls 18, co-operating therewith and actuated by a rocker-shaft 19. This rocker-shaft is oscillated by means of a steam-cylinder

20, its piston 21, and piston-rod 22, the piston-rod 22 being provided with a cross-head 23, having at each of its ends a gear-rack 24, each of which intermeshes with a segmental gear 25, fixed upon the rock-shaft 19. The movement of the piston is controlled by means of a valve 26, having a stem 27, actuated by means of a hand-lever 28.

All of the parts thus far designated are old in the art, and I do not limit myself to the particular forms shown.

The part of the device which is new and for which protection is sought is the adjustable stop mechanism for controlling the range of movement of the piston 21, and consequently of the shaft 19, and through them the advance movement of the shaft 15 and the standards or knees of the head-blocks. This stop mechanism consists of a lever-like arm 29, pivoted at 30 to a lug or bracket formed upon the bed-plate 31, by means of which the power mechanism is adapted for attachment to the carriage. This arm sweeps a segmental ratchet or quadrant 32, suitably supported by the power mechanism. The arm is provided with a spring-pawl 33 for engaging the teeth of the ratchet, this pawl being manually controllable by means of a bell-crank 34 in position to be grasped by the hand of the operator as he grasps the arm to move it. The arm 29 is provided with a contact-face 29^a, which lies in the path of the cross-head 23, and thus limits the forward movement thereof. The angular position of the arm 29 determines the stroke of the piston, the outward movement of which is stopped by the arm, the impact being sustained by the pivot 30 and the ratchet 32. The pivot 30 is located as near as practicable to the cross-head 23 and still provide a sufficient range of movement of the contact-face 29^a. The pivot 30 may be regarded as the fulcrum of the lever, and as it is located much nearer the point of impact of the cross-head than is the pawl 33 it carries the major portion of the burden. The lower end of the arm 29 is preferably bifurcated, so that it may be located centrally as to the cross-head 23, the shaft 22 passing between its legs. The segmental ratchet 32 is preferably slotted, the arm 29 passing through its slot, and the nose 35 of the pawl

33 is of sufficient length to engage both sides of the ratchet. The body of the pawl is bifurcated to receive the arm 29, to which it is pivoted. Along one side of the segmental ratchet 32 is located a graduated lineal scale 36, over which plays a finger 37, secured to the arm 29. The thickness of board cut from the log is determined by the position of the arm 29, and the scale 36 is so placed 10 that the mark thereon indicated by the finger 37 designates the thickness of the board. In practice it is found advisable to cut the logs into boards or planks of different thicknesses, and it is necessary that the set-works 15 be easily and quickly adjusted to make each cut as may be directed by the foreman. It is obvious that if the ratchet 32 be provided with teeth of sufficient fineness to adapt the machine for a fine grading of lumber as to 20 thickness it will be difficult for the operator to quickly and accurately set the log if reliance is had only upon the graduated scale 36. To overcome this difficulty, I provide removable templets 38 or auxiliary ratchet- 25 plates adapted for attachment to the segment, each having notches or teeth for the reception of the pawl 33, corresponding in location with the several dimensions into which the material being operated upon is to be cut, 30 the remainder of the face of the plates being plain and projecting above the teeth of the ratchet 32, the teeth 40 in the templet being, however, of sufficient depth to allow the pawl to engage the ratchet-teeth when it falls into them. The nose of the pawl is laterally extended, as shown at 41, so as to coöperate with 35 the templet.

The mill operator invariably acts under instructions to cut the particular material being operated upon into certain specified thicknesses—as, for example, one inch, one and one-fourth inches, and two inches—and the sawyer, being governed by the appearance of the log after each cut, indicates to the setting operator the thickness of the next board to be cut. In preparation for cutting the material to be operated upon the operator applies to the quadrant the plates corresponding with the dimensions stated in the order, 45 or specially prepares one by the use of a file by cutting the teeth at the proper locations. The templet or plate having been applied, the setter has to concern himself only with the several sets of teeth with which it is provided, 50 so that he can without the necessity of close scrutiny shift the lever 29 to the desired position.

I claim as my invention—

1. In a sawmill set-works, in combination,

a reciprocating head, a lever-like stop-arm 60 crossing the path of the head and being pivoted at one side thereof, and means for adjustably securing the swinging end of the stop.

2. In a sawmill set-works, in combination, 65 a reciprocating head, a lever-like stop-arm crossing the path of the head and being pivoted at one side thereof, a segmental ratchet or quadrant for coöperating with the swinging end of the stop-arm, and a pawl carried by such 70 arm for engaging the ratchet or quadrant.

3. In a sawmill set-works, in combination, a reciprocating part, an adjustable lever-like stop for determining the range of movement of such part, a removable notched plate for 75 determining the positions to which the stop-arm may be adjusted, and a pawl carried by such stop-arm for coöperating with the notched plate.

4. In a sawmill set-works, in combination, 80 a reciprocating head, a lever-like stop-arm crossing the path of the head and being pivoted at one side thereof, a segmental frame coöperating with the arm, a plate adapted to be removably secured to the frame and having notches so disposed as to determine the adjustment of the stop-arm, and a pawl carried by such arm for engaging the notches of the plate.

5. In a sawmill set-works, in combination, 90 a steam-cylinder, a piston reciprocating therein, a piston-rod leading from the piston, a cross-head fixed to the piston and having longitudinally-disposed gear-racks, a rocker-shaft having segmental gears intermeshing 95 with the racks, a lever-like stop-arm crossing the path of the cross-head and pivoted at one side thereof, a segmental ratchet coöperating with the stop-arm, a pawl carried by such arm for engaging the ratchet, a removable 100 templet for closing the teeth of the ratchet not desired for service against the entry thereinto of the pawl.

6. In a sawmill set-works, in combination, 105 a reciprocating part for actuating the setting mechanism, an adjustable lever-like stop-arm for limiting the range of movement of the reciprocating part, a segmental ratchet, a pawl carried by the stop-arm for coöperating with the ratchet and a removable notched 110 templet adapted to be secured to the ratchet to prevent the engagement of the pawl with any of the teeth thereof except such as correspond with the notches of the templet.
